UNITED STATES PATENT OFFICE

152,315

DESIGN FOR AN ELECTRICAL- CONNECTOR BODY

Herbert S. Barnhart, Scarsdale, N. Y., assignor to
The Whitney Blake Company, Hamden, Conn.,
a corporation of Connecticut

Application March 30, 1948, Serial No. 145,453

Term of patent 14 years

(Cl. D26—1)

To all whom it may concern:

Be it known that I, Herbert S. Barnhart, a citizen of the United States, residing at Scarsdale, in the county of Westchester and State of New York, have invented a new, original, and ornamental Design for an Electrical-Connector Body, of which the following is a specification, reference being had to the accompanying drawing, forming part thereof.

Fig. 1 is a perspective view of an electrical-connector body, showing my new design;

Fig. 2 is a face view thereof;

Fig. 3 is an edge view thereof; and

Fig. 4 is a view looking toward the outer end of the body.

The design is characterized by the oppositely-flaring panels on the respective opposite sides of the body.

I claim:

The ornamental design for an electrical-connector body, substantially as shown and described.

HERBERT S. BARNHART.
